UNITED STATES PATENT OFFICE.

JOHN J. FARRAR, OF RAPID CITY, SOUTH DAKOTA.

CONTAINER.

1,156,767.

Specification of Letters Patent. Patented Oct. 12, 1915.

Application filed August 20, 1913. Serial No. 785,659.

To all whom it may concern:

Be it known that I, JOHN J. FARRAR, a citizen of the United States, and a resident of Rapid City, in the county of Pennington and State of South Dakota, have invented a new and Improved Container, of which the following is a full, clear, and exact description.

My invention relates to a manner of packaging cement, lime, plaster and other loose materials that are subject to hard usage in handling and transportation.

The invention includes a novel container for the materials, an improved method of charging the container, and a novel package formed by means of the container.

The container is adapted to be filled with the cement or like material, and is composed of telescoping sections whereby receiving the material, the sections are telescoped together to compact the material into the form of a self-sustaining body for which the container forms a cover or envelop, the sections of the container being united to each other after the compacting of the material, to hold the latter in a substantially solid form. The ends of the container are formed in a novel manner to constitute end closures.

The invention will be more particularly explained in the specific description following.

Reference is to be had to the accompanying drawings forming a part of this specification, in which similar characters of reference indicate corresponding parts in all the views.

Figure 1 is a vertical section of a package of loose material enveloped by my improved container; Fig. 2 is a perspective view thereof; Fig. 3 is a longitudinal sectional view showing the container ready for filling; Fig. 4 is a fragmentary perspective view of one end portion of a tubular section of the container before forming the ends; Fig. 5 is an end view of a section partly finished; Fig. 6 is a vertical sectional elevation showing a modified form of the container; Fig. 7 is a view similar to Fig. 6, but illustrating a further modification; Fig. 8 is a view similar to Fig. 4, but showing a modified form of the end of a tubular section; Fig. 9 is an end view of a tubular section showing the end closure produced by the form shown

in Fig. 8; and Figs. 10 and 11 are end views showing further modifications of the end closure.

In carrying out my invention in accordance with the form of the container illustrated in Figs. 1 to 5, two tubular sections 10, 11, are provided, the one being of a size to snugly telescope within the other, the sections being approximately of equal length. Each section is formed with longitudinal slits 12, thereby producing a series of tongues 13. The slits may be parallel, as shown in Fig. 4, and an equal distance apart, and sufficient in number to produce pairs of tongues, the tongues of a pair being diametrically opposite each other. The tongues also may be of a length so that when folded inward over the end, opposite tongues will abut at the center of the end, as shown in Fig. 5, and the tongues may be folded in such succession that alternate tongues will overlap each other, providing a form of interlock.

In whatever order the tongues be folded, I provide on the interior of the end a covering 14 of cheese cloth, paper, or other suitable sheet material which is secured to the inner faces of the tongues by a suitable adhesive material. Similarly on the exterior of the folded tongues I apply a covering 15 of suitable sheet material, and secure the same by an adhesive.

In practice, the tongues are bent over a curved or approximately dome-shaped formation, the ends merging into adjacent side portions of the container on rounding lines. Also the slits 12 are cut to such a depth that the inward curving of the ends will start outward from the inner ends of the slit, and thus not have a marked tendency to bend sharply or crack in being turned inward.

The one tubular section is formed with a lateral inlet opening 16 between the ends thereof, through which the material is entered laterally into the container after the one section has been fitted to the other, as shown in Fig. 3. The ends of the sections when the container is to be charged are separated a sufficient distance to locate the inlet opening 16 beyond the inner end of the other section. A quantity of the material is entered into the container sufficient to more than fill one section and the sections

are then telescoped on each other until the inlet in the one section is closed by the other section. The continued collapsing of the sections under pressure will then compact 5 the material (indicated by the numeral 17 in Fig. 2) within the container into a practically solid body, which will be substantially self-sustaining and require that the container be only of sufficient strength to 10 form a reasonably strong envelop, the result being that the complete package may be handled after the manner of a stick of wood. It is to be observed that when the sections have been collapsed to a degree to thoroughly compact the material, the sections 15 are united to each other, which may be done by applying any adhesive material to the outer surface of the inner section at a point to be overlapped by the outer section when 20 the container is collapsed to the fullest extent.

The rounded end portions in practice, not only serve to avoid sharp angles on the package, but serve to crowd the material toward 25 the center at the end portions of the container, so that the material at the ends of the package will be compacted as fully as at other portions throughout the length of the package, and indeed will be packed to a 30 greater degree at the rounding portion, whereby the ends of the package, which will be subjected to perhaps greater ill usage, will maintain their form.

In the form shown in Fig. 6, a plain un- 35 slotted cylinder 20 is produced, and on each end thereof is a telescoping section 21, in the form of a cap, it being understood that the outer end of each telescoping cap is formed with tongues 13^a similar to the 40 tongues 13, the tongues being secured by inner and outer coverings 14^a, 15^a, as in the first described construction. With this form of container the package may be formed by removing one end cap and filling the cylindrical body 10 and the opposite cap 21, after 45 which the remaining cap is placed in position, there being a quantity of material projecting above the body for the material to be solidly compacted by forcing home the 50 cap under pressure.

In the form shown in Fig. 7, the body 20^a is formed at one end with integral tongues 13^b, which are secured by an inner covering material 14^b and an outer covering ma- 55 terial 15^b. The opposite end of the container is closed by a telescoping cap 21^a, the end of which is formed by tongues 13^c, having an inner covering 14^c and an outer covering 15^c, which may be similar to the coverings 60 14, 15. The form of container shown in Fig. 7 is filled in the same manner as that illustrated in Fig. 6.

In Figs. 8 and 9 I have shown pointed tongues 13^d which will all fold toward the 65 central point as indicated in Fig. 9.

In Fig. 10 the tongues 13^e are formed of such a length that the tongues of opposite pairs will overlap each other.

In Fig. 11 the tongues are formed the same as in Figs. 1 to 5, but are so folded that 70 opposite pairs will abut each other throughout their end portions, and successive pairs are merely folded, without overlapping edge-wise, as on the tongues of other pairs as in the arrangement shown in Fig. 5.

The outer container in all instances desirable has a vent-hole 22 near the top which will be closed by the inner section.

The container in practice, is made of sizes to contain standard quantities, such as are 80 now put up in ordinary sacks, bags, half barrels, etc., and my improved package possesses the advantage of being more conveniently handled, and more cleanly than ordinary sacks or the like, and the container is 85 of a character to prevent sifting of the material. Since the solid form of the contents makes it unnecessary that the container be more than an envelop, the container may be made of light cardboard or paper, which 90 may be formed by successive layers or coils one on top of another, after the manner of known forms or cardboard mailing tubes, etc.

The improved package also lends itself 95 to handling by machinery, which is not possible with ordinary cement bags.

Having thus described my invention, I claim as new and desire to secure by Letters Patent:

1. A container composed of telescoping tubular members adapted to compact a charge of material by end compression, said sections presenting dome-shaped ends to crowd the material at the ends of the container when the sections are telescoped, said dome-shaped ends comprising tongues constituting closures of the said ends, and dome-shaped layers of sheet material at the exterior and interior of the tongues and united 110 to the latter.

2. A container comprising a body formed of tubular sections having closed ends, one of said sections having a lateral charging opening between its ends, the said body sections being slidable on each other to cover the opening in the one section by the other section, the sections being capable of additional compressing movement after the closing of the opening to compress the contained 115 material after the opening is closed.

3. A container comprising a body formed of tubular sections having closed ends, one of said sections having a lateral charging opening between its ends, the said body sections being slidable on each other to cover the opening in one section by the other section, the sections being capable of continued movement to compress the material after the closing of the opening, the ends of the re- 120 125 130

spective sections merging into adjacent side portions thereof on rounding lines to crowd the material laterally at the ends of the container.

- 5 4. A container composed of telescoping tubular members adapted to compact a charge of material by end compression, said sections being formed of paper having longitudinal slits at the ends presenting tongues, 10 said tongues being inturned on rounding lines starting outward from the bases of the tongues and constituting end closures of the

container, and dome-shaped layers of sheet material at the interior and exterior of the tongues, the dome-shaped ends serving to 15 crowd a charge material at the ends as the members of the container are telescoped.

In testimony whereof I have signed my name to this specification in the presence of two subscribing witnesses.

JOHN J. FARRAR.
